DESIGN FOR A CHIN STRAP

Dolletta M. Ackerman, Los Angeles, Calif., assignor to Pauline Davis, Los Angeles, Calif.

Application December 2, 1941, Serial No. 104,431

Term of patent 7 years

To all whom it may concern:

Be it known that I, Dolletta M. Ackerman, a citizen of the United States, residing at Los Angeles, in the county of Los Angeles and State of California, have invented a new, original, and ornamental Design for a Chin Strap, of which the following is a specification, reference being had to the accompanying drawing, forming part thereof.

Fig. 1 is a perspective view of a chin strap showing my new design in the position it assumes when in use.

Fig. 2 is a front view on a slightly enlarged scale of the strap shown in Fig. 1.

Fig. 3 is a sectional view thereof on the line 3—3 of Fig. 2, and

Fig. 4 is a front perspective view of the chin strap.

I claim:

The ornamental design for a chin strap, as shown.

DOLLETTA M. ACKERMAN.
